L. J. FAIRBANKS

DISPENSER

Filed Feb. 10, 1920

Inventor,

Luke J. Fairbanks;
By ~~Agreement~~ ^{Agreement} of Luke
Attorney.

Patented June 12, 1923.

1,458,282

UNITED STATES PATENT OFFICE.

LUKE J. FAIRBANKS, OF LOS ANGELES, CALIFORNIA.

DISPENSER.

Application filed February 10, 1920. Serial No. 357,729.

To all whom it may concern:

Be it known that I, LUKE J. FAIRBANKS, a citizen of the United States, residing at Los Angeles, in the county of Los Angeles and State of California, have invented new and useful Improvements in Dispensers, of which the following is a specification.

This invention relates to improvements in dispensers, and more particularly to that 10 class of dispensers which are capable of expeditiously dispensing a semi-liquid mass, such as peanut butter, jams, apple butter and kindred mobile or plastic substances, at the will of the operator.

15 An important object of this invention is to provide a simply constructed, readily accessible, comparatively small, inexpensive, compact, durable and highly efficient dispenser, which is attractive and ornamental 20 in appearance and efficient in operation.

An object of the invention is to provide for preventing a hardening or settling of the heavy parts of any semi-liquid mass within the container chamber of the dispenser, to which end I provide means for 25 re-mixing the mass, thus keeping the mass at all times in its original consistency.

The invention further consists in the particular combination, inter-relation, construction, association and relative arrangement 30 of the several parts, elements and features of the dispenser, as illustrated in the drawing, described in this specification and finally pointed out in the claims.

35 Other objects and advantages will appear during the course of the following description:

In the drawing:

Figure 1 is a vertical elevation of the 40 dispenser;

Figure 2 is a vertical transverse sectional view of the device shown in Figure 1, taken on the line x^2-x^2 , and looking in the direction of the appended arrows;

45 Figure 3 is a detail plan view of certain elements of the dispenser, taken on the line x^3-x^3 , and looking in the direction of the appended arrows;

50 Figure 4 is a fragmentary, transverse sectional view of the dispenser showing a modified dispenser outlet;

Figure 5 is a fragmentary transverse view showing a further modification of the dispensing outlet shown in Figure 4;

55 Figure 6 is a fragmentary view of a dis-

penser container and cover and means for locking the last named elements together;

Figure 7 is a perspective view partly sectioned of one of the blade elements shown in Figure 3; and,

Figure 8 is a detail plan view partly sectioned of a handle means, and taken on the line x^8-x^8 , Figure 2.

Corresponding parts in all the figures are designated by the same reference characters.

Referring particularly to the drawing, the dispenser A includes as one embodiment of the invention a container B having a dispensing outlet C, a combined plunger and scraper D, an agitator or mixer E, both of which are arranged within the container; handle means F, and means G for rigidly holding the device to some fixed object.

More particularly the container B includes a cover 1 which is provided with downwardly directed edges 2 for gripping the rim of the container. A portion of the edge 2 of the cover is angularly slotted as at 3 to engage an outwardly projecting lug 4 mounted on the container. Thus a slight turn of the cover 1 acts either to engage the slot 3 with the lug 4, or to disengage same, whereby the container may be locked to the cover or easily removed therefrom, as desired.

Concentrically disposed within the base of the container is an aperture 5 around the edges of which is a downwardly projecting flange or collar 6.

The dispensing outlet C shown in Figures 1 and 2 includes a mouth-piece of cylindrical tubing 7, having one end thickened as at 8 to form a flange 9.

In order to secure the mouth-piece to the container B, the opposite end 10 of the cylindrical tubing 7 comprising same, is exteriorly threaded for a portion of its length, as at 11, to engage an interiorly threaded surface 12 of the flange 6.

A cut-off valve a comprising a disc 13 is 100 pivotally fastened to and held in position over the thickened end of the tubing 7 by means of a screw 14. To prevent the disc when covering the opening of the mouth-piece from being sprung by any undue 105 weight from the contents within the container, a Z-shaped bracket 15 is mounted on the top surface of the disc 13, as at 16, so that the free horizontal arm 17 of same normally engages the top surface of the flange 110

9 when the disc is closed, as shown in Figures 1 and 2.

The disc 13 has a depending extension or arm 18, which arm is for the purpose of 5 allowing the operator a purchase on same sufficient to facilitate easily reciprocating or closing the disc 13 over the end of the mouth-piece 7, when desired.

A modification of the dispensing outlet

10 C is shown in Figure 4 and is similar in all details to the outlet C of Figures 1 and 2, just described, with the exception that a mouth-piece 19 is in the form of a hollow frustum of a cone or an inverted funnel.

15 It should be particularly observed that while the inside surface of the hollow cone 19 is regular throughout, the outside peripheral surface near the shorter diameters is thickened to form a parallel side or cylindrical surface 20. This surface is provided with 20 threads 21, which threads engage the threads 12 of the flange 6.

A further modification of the dispensing outlet C is shown in Figure 5, in which a 25 mouth-piece 22 is in all respects similar to the mouth-piece 19 of Figure 4, except that the lip 23 of same is arcuated. The cut-off valve α includes a disc 24, the surface of which is arcuated to correspond to the lip 23.

30 Pivottally depending as at 25 from the flange 6 and at corresponding opposite sides thereof, are arms 26, which arms are fastened to the edge portion of the disc 24. To operate the valve α , a handle 27 is mounted 35 on the outside surface of the disc. To limit the reciprocating movement of the disc in one direction a check 28 is fastened to the mouth-piece 22 as at 29; this check has an arm 30 extending over the lip 23 and is capable of engaging the edge of the disc.

Within the container B is the circular plunger or scraper D having an opening or aperture 31 at its median portion and around 45 which is disposed a collar 32 integrally formed with the plunger. A sleeve shaft 33 has a portion of the peripheral surface of one end as at 34, flushly surrounded by the collar 32 and joined each to the other by means 35 passing through the collar 32 and embedded in the shaft 33, which shaft 33 in turn passes upwardly for a distance through 50 an aperture 36 in the cover 1. It might be mentioned that the aperture 36 is in co-axial alignment with the aperture 5 in the base of the container B.

55 Co-axially disposed within the sleeve shaft 33 is an extended central shaft 37, which carries a mixer or agitator E located 60 within the container B and below the plunger D.

65 The agitator E comprises a plurality of blade elements 38 spacedly arranged around and joined to a hub 39, which hub in turn is fixedly held to one end of the central shaft 37 by means of a lock bolt 40,

Referring to Figure 7, each blade 38 is given a longitudinal spiral set and pitched as shown by the transverse vertical section 41. While the depth of the blade as shown at 42 is constant throughout its length, the 70 surface 43, which in practice is the top surface of the blade, progressively varies in width from hub to tip, so that in contour it resembles a one-half crescent.

The handle F, provided with a detent 44 75 is slidably mounted upon the shaft 37. The detent includes two arms 45 and 46 integrally formed and at angles to each other. One of the arms 45 is pivotally mounted on the handle hub 47 by means of a bracket 48, while the other arm 46 passes through an aperture in the hub 47 and normally engages, when desired, any one of a plurality of internal recesses 49 longitudinally arranged on and located in the shaft 37. A spring 50 is so mounted between the arm 45 and the handle F as to exert an outward pressure against the arm 45, thus ensuring that the arm 46 will not slip out of any one of the recesses 49 until such time as the operator exerts a downward pressure against the arm greater than the outward pressure exerted by the spring.

The means G for securing the dispenser A 95 to some object, includes a bracket 51 provided near one end of same with fingers 52, which fingers in turn connect with the peripheral surface of the container B. The opposite end of the bracket is provided with adjustable clamping jaws 53 which include fixed and movable jaws 53 and 54 respectively. The fixed jaw 53 is placed under the object, and the movable jaw 54 which slides co-axially upon the arm 51 of the bracket G, is pressed downwardly on the opposite surface of the object and the lock bolts 55 and 56 turned.

The operation, uses and advantages of this dispenser are as follows:

To use a concrete example, suppose that the dispenser A is mounted upon a counter in a grocery store, and it is desired that the container B be used for peanut butter. At the present time peanut butter is seldom handled in grocery stores owing to the difficulty of successfully dishing same from any form of container. In my invention, the cover 1 is first removed from the container B, and the agitator E and plunger D likewise removed. The peanut butter is then poured into the container B and the plunger and agitator returned within the container and the cover replaced and locked. The plunger D of course will rest on top of the plastic substance, while the agitator E being small, will gradually sink to the bottom through the peanut butter.

To prevent this so that the hub 39 of the agitator E will not completely cover the dispensing outlet 5 of the container B, the

handle F is moved downwardly upon the shaft 37 and the detent 44 allowed to slip into one of the internal recesses 49 so that the hub of the handle 47 rests on the upper 5 end of the sleeve shaft 33.

Naturally the grocer would be desirous of ascertaining the cubic contents of the container B, and if possible the exact weight 10 of the peanut butter to be dispensed through the dispenser outlet C.

A scale 57 showing the cubic contents of the container B is marked longitudinally upon the sleeve shaft 33. There is likewise provided a scale 58 which designates the 15 number of pounds that might approximately be within the container B. I say approximately, because different plastic substances would vary in weight.

In practice, the sleeve shaft 33 is made 20 of wood, and the interior surface is lined with metal cribbing to reduce any wear that the shaft 37 might incur.

Now, if a customer were to desire say 25 three pounds of peanut butter, the grocer would place a small bucket beneath the dispensing outlet C and would press downwardly with one hand upon the sleeve shaft 33 and move the disc or closure means 13 past the mouth of the dispensing outlet C. 30 The peanut butter would now flow outwardly and into the bucket due to the pressure exerted by the plunger D. The grocer would at all times watch the scale 58 and when the plunger had moved downwardly 35 a sufficient distance, say to where it registered approximately three pounds on the scale 58, he would immediately close the disc 13 over the dispenser outlet C. The disc 13 being thin would act as a cutting 40 element and sever the contents discharged from the outlet C.

Figures 4 and 5 show a modified form of the dispensing outlet C which has been found more satisfactory than the dispensing outlet illustrated in Figure 1 and 2. 45 As previously described it is made in the frustum of a hollow cone, because plastic substances adhere less readily to a sloping wall than they do to a straight wall. Furthermore, it is much easier to successfully 50 clean a dispensing outlet of the type shown in Figures 4 and 5 than that shown in Figures 1 and 2.

Let us suppose that the peanut butter 55 within the container B becomes hardened; the oil will rise to the surface and the hard substance will drop to the bottom. Naturally it would be impossible now to remove any of the peanut butter through the dispensing outlet C, regardless of any pressure 60 that might be exerted by the operator upon the plunger D. To overcome this condition the agitator E is so disposed within the container B that it may be reciprocated or rotated in accordance with movement of the

shaft 37. By a combined rotation of the shaft 37 aided by the handle F and reciprocation, the peanut butter may be thoroughly re-mixed and returned to its original consistency, at which time it will be possible 70 to again successfully dispense same. Furthermore, the blades 38 are given a spiral set and a negative pitch in order that the plastic substances within the container B may be moved to a common center when the 75 agitator E is rotated.

It is obvious that many changes and variations and modifications may be made in departure from the particular description and showing of the accompanying drawing 80 in adapting the invention to varying conditions and requirements of use and service, without departing from the true spirit of the invention.

Having thus disclosed my invention, I 85 claim and desire to secure by Letters Patent:

1. In a dispensing device, the combination with a container provided with a discharge opening, a central shaft, an agitator carried 90 by said shaft, and a sleeve shaft surrounding said central shaft, a plunger carried by said sleeve shaft, both said agitator and said plunger being within the container and capable of reciprocal motion within same. 95

2. In a dispenser, a container provided with a discharge opening, means for closing the opening and for movement across the opening to sever the contents to be discharged therefrom, a sleeve shaft, a combined scraper and plunger mounted upon 100 said shaft, a shaft co-axially disposed within the sleeve shaft, an agitator carried at one end of the sleeve shaft, and below the plunger, both said plunger and agitator being 105 within the container, the plunger being adapted to reciprocate with said shaft independent of any movement of the agitator shaft.

3. In a dispenser, a container provided 110 with a discharge opening, a mouth-piece surrounding the discharge opening, means for closing the mouth-piece and for movement across the mouth-piece to sever the contents to be discharged therefrom, a sleeve shaft, a combined plunger and scraper mounted upon the end of said sleeve shaft within the container and adapted to engage 115 with the interior wall thereof, whereby material adhering to the wall is dislodged by reciprocating said shaft, a central shaft co-axially disposed within the sleeve shaft, and an agitator carried at one end of the sleeve shaft and below the plunger. 120

4. In a dispensing device, a container 125 having a discharge opening, a central shaft, an agitator carried by the shaft, a sleeve shaft surrounding said central shaft, a combined plunger and scraper mounted on the sleeve shaft and above the agitator, both 130

- 5 said agitator and said plunger being contained within the container, and means joining said central shaft externally of said container, whereby the agitator may be reciprocated and rotated with said shaft.
5. In a dispensing device, a container having a discharge opening, a central shaft, an agitator carried by the shaft, a sleeve shaft surrounding said central shaft, a combined plunger and scraper mounted on the sleeve shaft and above the agitator, both said agitator and said plunger being contained within the container, and means joining said central shaft externally of said container, whereby the agitator may be reciprocated and rotated with said shaft; said means comprising a handle rotatably journaled on said central shaft, a detent on said handle in engagement with an internal recess in said shaft, whereby movement of the handle will rotate or reciprocate said shaft and the agitator member.
6. In a dispensing device, a container having a discharge opening, a central shaft, an agitator carried by the shaft, a sleeve shaft surrounding said central shaft, a combined plunger and scraper mounted on the sleeve shaft and above the agitator, both said agitator and said plunger being contained within the container, and means joining said central shaft externally of said container, whereby the agitator may be reciprocated and rotated with said shaft; said agitator comprising a plurality of radiating curved blades.
7. In a dispensing device, a container having a discharge opening, a central shaft, an agitator carried by the shaft, a sleeve shaft surrounding said central shaft, a combined plunger and scraper mounted on the sleeve shaft and above the agitator, both said agitator and said plunger being contained within the container, and means joining said central shaft externally of said container, whereby the agitator may be reciprocated and rotated with said shaft; said agitator comprising a plurality of radiating curved blades, each of which is downwardly inclined and given a longitudinal spiral set.
8. In a dispensing device, the combination with a container having a discharge opening at its lower end, a mouth-piece removably surrounding the discharge opening, a cutting element arranged to reciprocate across said mouth-piece, a shaft, agitators carried by said shaft within the container adapted to reciprocate and rotate with said shaft; said agitator comprising a plurality of radiating curved blades, each of which is downwardly inclined and given a longitudinal spiral set, whereby any plastic substance within the container may be directed toward the dispensing outlet.
9. In a dispensing device, a container formed with a discharge opening, a plunger and a reciprocal agitator within said container, and means for dispensing any content within the container through the discharge opening in predetermined amounts.
10. In a dispensing device, a container formed with a discharge opening, a plunger and a reciprocal agitator within said container, and means for dispensing any content within the container through the discharge opening in predetermined amounts; means likewise being provided for normally maintaining said discharge opening closed.
11. In a dispensing device, a container open at one end, and formed with a discharge opening in the base thereof, a reciprocal plunger and agitator within said container, and means for dispensing any content within the container through the discharge opening in predetermined amounts.
12. In a dispensing device, the combination with a container, provided with a discharge opening, a central shaft, an agitator carried by said shaft, a plunger, both said agitator and plunger being within the container and capable of independent reciprocal motion within the same; there being means for moving said plunger, the said agitator being beneath the plunger.
13. In a dispensing device, the combination with a container, provided with a discharge opening, of an agitator and a plunger within the container and capable of independent reciprocal motion within the same; said agitator being beneath the plunger.
